UNITED STATES PATENT OFFICE.

LEO SIMMONS, OF WASHINGTON, DISTRICT OF COLUMBIA.

GUARD FOR PROTECTION AGAINST HOLDUP-ROBBERS AND THE LIKE.

1,374,770.

Specification of Letters Patent. Patented Apr. 12, 1921.

Application filed July 8, 1920. Serial No. 394,721.

To all whom it may concern:

Be it known that I, LEO SIMMONS, a citizen of the United States of America, and resident of Washington, District of Columbia, have invented certain new and useful Improvements in and Relating to Guards for Protection Against Holdup-Robbers and the like, of which the following is a specification.

10 This invention relates to certain improvements in and relating to guards for protection against robbers, particularly those of the so-called hold-up type; and the objects and nature of the invention will be readily understood by those skilled in the art in the light of the following explanation of the accompanying drawings illustrating what I now believe to be the preferred mechanical expression or embodiment of my invention from among other forms, constructions and arrangements within the spirit and scope thereof.

An object of the invention is to provide a guard for the protection of a watchman or of a bank teller, clerk or counting house, mail, express, store, or hotel employee, which is capable of easy horizontal rotation by the hand or arm of the occupant, preferably the arm of the hand carrying a suitable offensive weapon, and to provide the guard with suitable means for supporting the freely rotatable guard in an elevated position to afford the occupant thereof unobstructed view and shooting range from 35 above the level of the heads of persons in the inclosure protected by the guard, and to render the guard quickly and easily accessible to the employee to occupy the same from the floor, should a hold-up robber be 40 tray his presence in the room or other inclosures protected by the guard, and preferably to provide a non-rotary floor or support for the occupant of the guard.

With these and other objects in view the invention consists in certain novel features of construction, and in combinations and arrangements as more fully and particularly set forth and specified hereinafter.

Referring to the accompanying drawings—

Figure 1, shows in perspective, a guard embodying my invention, included in the partition and counter of any suitable room or inclosure, such as a banking or other

room where money, securities or other valuable are usually accessible during business hours. 55

Fig. 2 is a vertical section through the counter or partition and the guard and its support. 60

Fig. 3 is a horizontal section taken in the plane of the line 3—3, Fig. 2. 65

Fig. 4 is a perspective view of certain details.

In the particular example illustrated, I show the partition 1 and counter 2 of any room or other inclosure wherein valuables such as money, securities, precious stones, jewelry, etc., are more or less accessible during business hours, and wherein the floor 70 3 is more or less open and accessible to the public for transaction of business with those behind or adjacent to the partition and counter.

In the particular application and embodiment of my invention that I have selected for illustration by the accompanying drawings, I have shown the rotary guard of my invention, elevated above the partition and so arranged that the occupant can look down 80 on all persons on the floor 3 in front of the partition as well as on persons behind the partition, with the guard support or base included in the partition and counter, and so constructed and arranged as to render the 85 guard readily and quickly accessible to the employee behind the counter adjacent to the guard, while said support and the guard are closed against entrance of persons from floor 3 in front of the partition and counter. 90

In this example, I show a hollow upright metal base suitably fixed to and erected on the floor in the line of the partition so as to be included therein and also set back in the counter and rising above the level 95 thereof. This base can be composed of metal uprights 4^a to which metal plates 4^b are secured to complete the break in the partition and to close the base from the front. To the rear of the line of the partition, and usually, below the level of the counter, the base is entirely open. 100

Any suitable freely rotatable cap or guard 5 is mounted on and rises from this base. In the example illustrated, the upper 105 ends of the base uprights 4^a support and are fixedly secured to a rigid horizontal annulus or ring 4 carrying grooved rollers

4^c, and the guard 5 is provided with a bottom ring or track 5^a fixed to the guard and resting on said rollers which thereby support the guard and render the same freely 5 rotatable horizontally.

The guard is provided with depending arms 5^b outside of the guard supporting ring 4 of the base, with their free ends deflected laterally to project under said ring 10 and thereby prevent displacement of the guard from the base. The plates 4^b of the base can, if so desired, project upwardly around the ring 4 to shield the same and the arms 5^b.

15 The guard 5 is preferably in the form of a more or less strongly constructed bullet proof (although not necessarily so) shell having top 5^c and surrounding wall 5^d and open at the bottom within the track ring 5^a. 20 This shell forms a unitary structure that is freely rotatable, as such, on the rollers or any other turntable or pivot support that may be provided therefor.

25 The surrounding wall 5^d is preferably more or less bullet proof, and so formed that the occupant of the guard can more or less freely observe the persons on the floor within the room where the guard is located. The guard can be variously formed and 30 constructed so as not to interfere with the view and vision of the occupant, although in the specific example illustrated, I show the guard formed with surrounding side windows closed by approximately bullet 35 proof transparent walls or plates 5^e.

The vertical or surrounding wall 5^d of the rotary cap or guard 5 is provided with a radial arm hole 5^f for the occupant, and the guard is provided with an exterior projecting hand or arm rest 5^g in approximate outward and downward continuation of said opening and in the form of a projecting approximately bullet proof rigid trough secured to the cap or guard to receive the 40 hand of the occupant that carries a fire arm or other means for projecting a protecting liquid, gas or projectile for disabling the 45 robber.

The occupant of the guard can project his 50 hand or arm through the opening and into the guard and thereby quickly and easily rotate the guard in either direction, to direct the offensive weapon against the robber located at any position in the room. 55 The trough or protection 5^g will serve to protect the hand against upwardly directed projectiles fired by the robber.

The base 4^a, 4^b is provided with any suitable elevated support or floor on which the 60 occupant of the guard can stand or sit while locating the robber, rotating the guard, and taking offensive action against the robber. This floor does not rotate with the guard but is carried by the base independently of the rotary guard.

For instance, I show horizontal floor 6 suitably mounted in the base a distance below the rotary guard, and if so desired, this floor can completely span the interior of the base and be formed by a fixed floor 70 section having a vertical man hole normally closed by an upwardly swingable floor section or trap door 6^a. By this arrangement, the employee can move up through the man-hole, elevating the hinged floor section, 75 which drops down to close the manhole, when the employee steps onto the fixed portion of the floor.

If the elevation of the floor 6, 6^a, is such as to render it inconvenient for the employee to quickly climb through the man-hole, I can provide any suitable step or intermediate support within the hollow base, on which the employee can stand and from which elevated position, he can easily pass 85 through the manhole onto the fixed floor 6. For instance, I show step 7 supported by and fixed in the base for this purpose.

It will be noted that the inner side of the base is entirely open under the counter 2, 90 so that an employee, behind the counter, the instant he becomes suspicious that a hold up is planned, can drop under the counter and easily and quickly enter the hollow base and climb to the floor 6 and 95 occupy the rotary guard. This guard and its base can be erected and located, at any situation where valuables, money, securities, express matter, or mail, are likely to be present and hence subject to attack.

100 It is evident that various changes, modifications and variations might be resorted to without departing from the spirit and scope of the invention and hence I do not wish to limit myself to the exact disclosures 105 hereof.

What I claim is:—

1. A protecting guard embodying a fixed hollow base, a guard mounted thereon and consisting of an open-bottom freely horizontally-rotatable cap, a supporting floor secured in said base adjacent the open-bottom of said guard and normally closing the interior of said base from the guard, and means permitting passage through said floor 115 from the base into the guard.

2. A protecting guard embodying a vertical hollow supporting base having a side entrance opening and an occupant supporting floor above said opening, and a freely- 120 rotatable guard cap mounted on said base and accessible from said floor.

3. An elevated freely-horizontally rotatable guard having an arm opening therethrough and an exterior arm rest extending 125 from said opening, in combination with a fixed base on which the guard is mounted and freely rotatable, said base providing a support for an occupant of the guard whereby the said guard is rotatable by the occu- 130

4. An elevated freely rotatable observation guard having an arm hole and exterior hand rest, and a base on which the guard is freely rotatable, by the hand of an occupant of the guard within and supported on said hand rest on the exterior of the guard.
5. A hollow stationary base provided with an elevated fixed floor or support adjacent the upper end thereof, in combination with a freely rotatable observation guard mounted on said base above said fixed floor or support and adapted to be freely rotated by the hand or arm of the occupant while standing on said support.
6. A hollow fixed base included in a counter or partition and open at the rear and having an elevated floor or other support above said counter or partition and freely accessible through said rear opening, and an observation and offensive guard freely rotatable on said base by the occupant located on said floor or support.
7. A hollow fixed base included in a counter or partition and having an elevated floor or other support above said counter or partition and an observation and offensive guard on said base above said floor or support and freely rotatable thereon.
8. A hollow fixed base included in a counter or partition and having an elevated floor above said counter or partition, an observation and offensive guard rotatably mounted on said base above said floor, and means in said floor to permit passage therethrough from the interior of said base to said guard thereabove.
9. A hollow fixed base included in a counter or partition, an occupant supporting floor at the upper end of said base above said counter or partition, an observation and offensive guard rotatably mounted on said base above said supporting floor, an upwardly opening door to permit passage of the occupant from the interior of said base into said guard and adapted to be closed against entrance to said guard when occupied, and said guard adapted to be freely rotated by the hand or arm of the occupant.
10. The combination with a counter or partition, of a hollow vertically disposed base extending upwardly therefrom and having a side entrance accessible from beneath said counter or partition, and an observation and offensive guard rotatably mounted on said base above said counter or partition, said base provided with means for closing said guard against entrance thereto.
11. A hollow fixed base included in a counter or partition, an elevated support mounted in said base above said counter or partition, an observation and offensive guard rotatably mounted on said base above said floor said guard provided with a side arm opening therethrough, and an exterior hand rest extending from said opening and forming a hand protection and support upon which an occupant of the guard projects and rests an arm and hand to train an offensive weapon upon the space around and below said elevated guard, said exterior hand rest providing means by which the occupant rotates said guard.
12. A hollow fixed base included in a counter or partition in lateral continuation thereof and substantially vertical continuation thereabove and accessible from beneath said counter or partition, and an observation and offensive guard mounted and freely rotatable on said base upon the counter or partition, said guard accessible from said base and providing means from which the space around said partition or counter may be observed to prevent attack thereupon.
13. A protecting guard comprising a hollow fixed base, a floor or support at the upper end of said base, an observation and offensive guard rotatably mounted on said guard above said floor or support, and a door in said floor through which access is had to and from the interior of said guard.

LEO SIMMONS.
